Des. 236,042
Patented July 29, 1975

236,042

SHOE PROTECTOR

William F. Martin, 350 Stonycroft Road,
Ridgewood, N.J. 07450

Filed July 16, 1973, Ser. No. 379,246

Term of patent 14 years

Int. Cl. D2—04

U.S. Cl. D2—271

FIG. 1

FIG. 3

FIG. 2

FIG. 4

FIG. 5

FIG. 7

FIG. 6

FIG. 1 is a side elevational view of a shoe protector showing my new design;

FIG. 2 is a top plan view thereof;

FIG. 3 is a front elevational view;

FIG. 4 is a rear elevational view;

FIG. 5 is a bottom plan view;

FIG. 6 is a top perspective view; and

FIG. 7 is a cross sectional view taken on the line 7—7 of FIG. 2.

I claim:

The ornamental design of the shoe protector, as shown.
